UNITED STATES PATENT OFFICE

AXEL F. CARLSON, OF CAMBRIDGE, MASSACHUSETTS, ASSIGNOR TO THE REECE BUTTON HOLE MACHINE COMPANY, OF BOSTON, MASSACHUSETTS, A CORPORATION OF MAINE

THREAD TRIMMER FOR SEWING MACHINES

Application filed January 22, 1927. Serial No. 162,890.

This invention relates to sewing machines of that class which are constructed to perform a predetermined sewing operation and then automatically come to rest, (a button-hole sewing machine being an exemplification of a sewing machine of this type), and particularly to means for trimming the thread at the end of the sewing operation.

In sewing machines of the type above referred to the stitch-forming mechanism and work-holding means have a relative feeding movement during the sewing operation and in some sewing machines of this type the stitch-forming mechanism and the work-holding means have a further relative movement after the sewing operation is completed during which further relative movement a length of thread is drawn through the throat plate. In a buttonhole sewing machine this further or additional relative movement between the stitch-forming mechanism and work-holding means which occurs after the stitching is completed is usually for the purpose of carrying the parts from stitching position to buttonhole cutting position. As stated above during this relative movement by which the parts are brought relatively into buttonhole cutting position a length of thread will be drawn out through the throat plate and the present invention has for its object to provide novel means for cutting this thread close to the work.

The stitch-forming mechanism is brought to rest at the end of the stitching operation with the needle raised and frequently at this time a loop of needle thread is retained by some part of the under-thread-manipulating mechanism, such for instance as the looper. Consequently during the relative movement between the stitch-forming mechanism and work-holding means which occurs after the stitch-forming mechanism has come to rest the threads which are drawn out through the throat plate by such relative movement include the loop of needle thread, the under thread, if one is used, and also the cord, if the machine is a buttonhole sewing machine using a cord.

In order to trim these threads positively and accurately I have provided herein a pull-

down device which is actuated to engage the thread or threads beneath the work and pull them down away from or separate them from the work and I have provided a cutter operating in a plane parallel to the plane of the work which is adapted to cut the thread between the pull-down and the work. The operation of the pull-down separates the thread from the work and places it in position to be acted on by the cutter.

In some sewing machines of this type the under-thread-manipulating mechanism is mounted on a turret which is turned at each end of the buttonhole to carry the stitching around the buttonhole end and one feature of my present invention relates to a construction by which the pull-down device is actuated by the movement of the turret which occurs after the stitching operation has been completed.

In the present invention the thread cutter is actuated subsequent to the releasing of the work clamps so that when the thread is cut the work is unclamped. In accordance with this feature of the invention the thread cutter is actuated in conjunction with the means for releasing the work clamps, the two devices being so timed that the work clamps are released first and then the thread is cut.

The device herein shown is further provided with means for so manipulating the under thread that a proper length will be left after the cutting operation to start the stitching on the next seam.

In order to give an understanding of the invention I have illustrated in the drawings a selected embodiment thereof which will now be described after which the novel features will be pointed out in the appended claims.

Fig. 11 is a sectional view taken at right angles to Fig. 10, and showing the pull-off device illustrated in said Fig. 10.

Before proceeding to describe the features included in the present invention I will refer briefly to the sewing machine as a whole and to the parts which are of known construction and are common to other sewing machines of this type.

The work 1 on which the stitching is to be performed is clamped to the bed 3 by means of work clamps 4 which clamp the work against clamp plates removably carried by the bed and situated directly beneath the work clamps 4. These work clamps 4 are carried on pivoted arms 5 as usual.

The stitch-forming mechanism comprises the usual needle 6 which operates from above the work and a thread-manipulating mechanism 99 located below the work and which I will hereinafter refer to as the "under-thread manipulating mechanism" because it is situated beneath the work.

The needle 6 and the under-thread-manipulating mechanism 99 co-operate to concatenate the stitches in usual manner.

The stitch-forming mechanism is carried by a suitable frame 7 which is mounted on the bed 3. Said stitch-forming mechanism and work-holding means have a relative movement as usual in sewing machines of this type and while this relative movement may be secured either by moving the work-holding means or by moving the stitch-forming mechanism yet in the particular embodiment of the invention herein shown it is secured by movement of the stitch-forming mechanism, the frame 7 being slidably mounted on the bed 3 and means being provided for giving the frame 7 a movement both during and after the stitching operation.

In this device, therefore, the work is clamped on the stationary bed and the feeding of the work relative to the stitch-forming mechanism is performed by the back and forth movement of the frame 7.

The operation of the machine is controlled through the usual main cam 8 which is carried by the frame 7.

In sewing machines of this type it is a common practice to mount the under-thread-manipulating mechanism on a turret 29 which is rotatably mounted in bearings in the depending portion 30 of the frame, said turret carrying the usual throat plate 31 that is situated directly beneath the needle 6 and is provided with the usual opening through which the needle operates and through which the thread is led to the work 1. This turret is rotated at the ends of the buttonhole to carry the stitching around the buttonhole ends in usual manner.

The opening and closing of the clamps 4 is controlled by a toggle lever device of known construction and it comprises two toggle members 9 and 10 pivoted together at 11, the toggle member 10 being pivoted to the bed 3 at 12, and the toggle member 9 being pivoted to a bracket arm 13 depending from a swinging frame 14 which is pivoted to the bed at 15. This frame has at its rear end a lip 16 which engages another lip 17 formed on an arm 18 that is rigid with the clamp arms 5, these clamp arms being pivoted at 19. The toggle member 10 is extended to form a handle 20 by which the clamps may be manually closed. When the toggle members 9, 10 are straightened the bracket arm 13 will be forced downwardly. This downward movement will bring the lips 16, 17 into engagement and thus swing the clamps downwardly in a well-known way, the clamps being held downwardly by the straightened toggle. The bracket arm 13 has a pulling spring 21 secured thereto which elevates the bracket arm 13 and frame 14 when the toggle is broken.

The clamps are automatically closed when the machine is started in a well known way through the medium of a lever 22 which is pivoted at 23 and is provided with a roll 24 adapted to be acted on by a cam surface 25 on the main cam 8.

The toggle arm 9 is provided with a lateral extension 26 situated to be engaged by the end of the lever 22 when the latter is depressed by the cam 25, the engagement of the lever 22 with the arm 26 serving to straighten the toggle as will be readily understood and thereby closing the clamps. This operation occurs as soon as the machine is started.

The machine herein shown is also provided with means for cutting the buttonhole. In the construction shown this comprises a buttonhole cutter 27 and an anvil or bed member 28 which is mounted on an arm 101 pivoted to the frame 7. This arm 101 is controlled by the usual main cam 8 and when it is depressed it forces the work down onto and over the buttonhole cutter 27 thereby to cut the buttonhole slit.

The parts thus far described are or may

be all as usual in sewing machines of this type, exemplifications of which may be found in United States Patents No. 1,352,280, September 7th, 1920, and No. 1,558,182, October 5, 1925.

The operation of the machine, except for the thread-trimming devices, is in general as follows. Whenever the machine has been brought to rest at the end of a sewing operation the cam 8 will be so situated that the cam projection 25 is immediately adjacent the roll 24 and when the machine is started in operation the first or initial movement of the cam 8 will cause the cam projection 25 to depress the lever 22 thereby causing said lever to act against the arm 26 and straighten the toggle 9, 10 to close the clamps 4 onto the work 1. The stitching then proceeds down one side of the buttonhole and back along the other 15 side, there being a relative movement between the stitch-forming mechanism and the work-holding means during the stitching along the sides of the buttonhole and the turret 29 having a turning movement at the ends of the 20 buttonhole. When the sewing operation is completed the parts will be in substantially the position shown in Fig. 8, one end of the buttonhole 32 which has been sewed being directly over the throat plate 31 and the work 30 1 being still clamped by the work clamps 4.

After the stitch-forming mechanism has come to rest then the work-holding means and stitch-forming mechanism are given a relative movement by which the work is relatively carried to the position shown in Fig. 9, the buttonhole 32 being brought into position over the cutter 27 and in position to be acted on by the cutter block 28. When the stitch-forming mechanism comes to rest 40 there will be a loop 33 of the upper thread 34 retained by the loopers of the under-thread-manipulating mechanism and when the relative movement between the stitch-forming mechanism and work-holding means 45 occurs subsequent to the sewing operation such relative movement will draw out a length of thread or threads through the throat plate, such length comprising an elongation of the loop 33 of needle thread 34, a 50 length of under thread 35, if an under thread is used, and a length of stay cord 36, if a stay cord is used. These threads which are thus drawn out will lie along under the work as indicated by dotted lines at 37 in Fig. 9. When the parts arrive relatively at the 55 position shown in Fig. 9 then the cutter block 28 is actuated to cut the buttonhole in a well known way.

My invention has for its object to provide 60 novel means for cutting close to the work the thread or threads 37 which extend from the work to the throat plate after the work has been carried relatively into buttonhole cutting position. The threads normally lie 65 closely adjacent to the work and substan-

tially parallel thereto and in order to cut or trim the threads in a sure and satisfactory manner I provide a pull-down device which operates to pull the threads indicated by the dotted lines 37 in Fig. 9 down away from the work 1 as shown in full lines Fig. 9 thus separating the threads from the work and bringing the threads into position to be acted on by the cutter which cuts the thread between the pull-down and the work.

The pull-down herein shown comprises two thread-gripping fingers 38 and 39 which are mounted to move toward each other in a plane parallel to the work and thereby grip the threads between them and then have a downward swinging movement to carry the threads away from the work 1. These pull-down fingers are pivotally mounted at 42 on the bed 3. Each arm is provided with a cam slot, said slots being indicated at 43 and 44 respectively. These slots receive a roll 45 mounted on an arm 46 pivoted to the bed at 47. The rear end of the slots 43, 44 are inclined relative to each other and are so arranged that a swinging movement of the arm 46 causes the arms 40, 41 to swing toward and from each other.

During the sewing operation the parts are in the position shown in Fig. 2 and the pull-down fingers will be separated from each other. After the sewing operation is completed and during the relative movement between the stitch-forming mechanism and work-holding means by which the parts are carried to buttonhole cutting position and the length of thread is drawn through the throat plate 31 as shown at 37, the arm 46 is swung forwardly into the position shown in Fig. 3 thereby acting through the cam slots 43, 44 to swing the arms 40, 41 toward each other. During this movement the length of thread which has been drawn out is grasped by the two pull-down fingers.

It will be noted that each pull-down finger is provided at its end with a thread-receiving notch 48 and that the pull-down finger 38 has two extensions 49 while the pull-down finger 39 has the four extensions 50. These extensions are adapted to have interlocking engagement when the two pull-down fingers are brought relatively into the position shown in Figs. 3 and 7 at which time the length of threads are confined in the two notches 48. The extensions 49 and 50 at this time have an overlapping relation so that the thread is positively retained in the aligned notches 48, the two notches forming a sort of eye through which the threads extend. The shape of the upper extension 49 is such that during the swinging movement of the pull-down fingers from the position shown in Fig. 2 to that shown in Fig. 7 said upper extension 49 will find its way between the length of thread and the work and thus 125 130

guide the length of thread or threads into the notch 48.

After the two pull-down fingers have been carried into the position shown in Fig. 7 so that the threads are confined in the notches 48 then the ends of said fingers are swung downwardly thus separating the threads from the work. For this purpose the fingers are pivotally mounted to the arms 40, 41.

The finger 38 is shown as fast on a rock shaft 51 which extends longitudinally of the arm 40 and is journaled in an elongated bearing 52 formed therein. The finger 39 is similarly fast on a rock shaft 53 which is journaled in an elongated bearing 54 formed on the end of the arm 41. Both fingers 38, 39 are acted upon by springs 55 which normally hold them in their raised position.

For giving these pull-down fingers 38, 39 their downward swinging movement by which the length of thread or threads is separated from the work I have provided means which is actuated by the arm 46. It will be remembered that one end of the slots 43, 44 in the arms 40, 41 have an inclined relation to each other. The other ends 56 of the slots are so shaped that when the arms 40 and 41 are in the position shown in Fig. 3 the ends 56 of the two slots are in alignment with each other and are concentric to the pivot 47. Consequently during the initial swinging movement of the arm 46 the arms 40, 41, will be swung toward each other and during the final movement of the arm 46 the pin 45 will merely move in the concentric portions 56 of the slots and the arms 40, 41 will remain stationary.

Means are provided whereby during the final swinging movement of the arm 46 the pull-down fingers 38, 39 will be given their pull-down movement. For this purpose the arm 46 is shown as having a cam 57 thereon which is adapted to engage an arm 58 formed on the rock shaft 51. The cam 57 is so positioned that it engages the arm 58 just as the roll 45 reaches the concentric portions 56 of the slots and, therefore, during the final swinging movement of the arm 46 the cam 57 will engage the arm 58 and thus rock the shaft 51 in a direction to swing the free end of the pull-down finger 38 downwardly. Since the two fingers are interlocked or geared together by the extensions 49 and 50 the downward swinging movement of the finger 38 will be communicated to the finger 39, the rock shafts 51, 53 constituting the axes about which the fingers turn. By this operation the length of thread, which is indicated at 37 in Fig. 9 which extends between the throat plate 31 and the sewing point, is pulled down away from the work as shown by full lines Fig. 9 thus placing the thread in position to be acted on by thread cutters. These thread cutters are indicated at 59, 60 and they are mounted on swinging

arms 61, 62 that are pivoted to the bed at 63, 64, respectively. The arms operate in planes parallel to the work and are adapted to swing from their open position shown in Fig. 3 to their closed thread-cutting position shown in Fig. 4. This swinging movement of the thread cutters by which the thread is cut occurs after the thread has been pulled down as shown in full lines Fig. 9, said cutters acting on the pulled down thread close to the work.

While any approved means may be employed for operating the pull-down fingers and the cutters I have herein shown a construction wherein the pull-down fingers are actuated by the movement of the turret which occurs after the sewing has been completed and the thread cutters are actuated by the means which are employed to unclamp the work or release the clamps 4. For operating the pull-down fingers from the turret I have secured to the turret a cam extension 65 having a cam groove 66 and the arm 46 has rigid therewith another arm 67 provided with a roll or follower 68 adapted to operate in said groove 66 as the turret moves. The arms 46 and 67 are both shown as rigid with a rock shaft 47 which extends through the bed so that they operate as a unit. The cam groove 66 is open at both ends and the parts are so arranged that during the final relative feeding movement between the stitch-forming mechanism and work-holding means the turret will be so positioned that one end of the open cam groove 66 is in line with the follower 68 as seen in Fig. 2.

After the sewing operation has been completed and the stitch-forming mechanism has been brought to rest then during the further relative movement between the stitch-forming mechanism and work-holding means by which the parts are brought to buttonhole cutting position the follower 68 enters the end 69 of the cam groove 66 and as the turret is moved forward by the forward movement of the frame 7 by which the parts are brought relatively to the position shown in Fig. 9 the follower 68 is carried through the cam slot 66 to the point 70 and during its travel through this cam slot the arm 46 is swung thereby to close the pull-down fingers together as shown in Fig. 3 and then to cause the cam 57 to engage the arm 58 and thereby produce the pulling down motion of the pull-down fingers 38, 39. As the follower 68 completes its travel through the slot 66 or from the point 70 to the point 71 the arm 46 will be swung in the opposite direction thereby positively opening the pull-down fingers away from each other and restoring them to their normal position. This operation occurs after the threads have been cut and during the turning movement of the turret which follows the forward movement of the frame 7. 103 is a spring acting on the arm 67 and

which holds it yieldingly in its normal position. Thus the travel of the follower from the end 69 of the cam to the point 70 will cause the pull-down fingers to first move toward each other to grip the thread and then swing downwardly to pull the thread away from the work as above described and the reverse movement of the arm 46 caused by the travel of the follower 68 from the point 70 to the end 71 of the cam will return the pull-down fingers to their normal position shown in Fig. 2.

After the thread has been pulled down then the cutters 59, 60 are operated to cut the pulled down thread between the pull-down fingers and the work. These cutters are actuated in conjunction with the means for releasing the clamps and are given their cutting movement immediately after the clamps are released. Both the cutter and the clamp-releasing means are controlled by the cam 8.

The cutter-carrying arms 61, 62 are provided with extensions 72, 73 and these extensions are connected by a toggle device comprising the two toggle members 74, 75 which are pivoted to the extensions at 76 and 77 and are pivoted together at 78. The toggle member 75 is provided with an extension 81 which has pivotally connected thereto one end of a link 82, the other end of said link being pivoted at 83 to a rocking member 84. This member 84 is pivotally mounted at 85 to the bracket arm 13.

During the sewing operation and while the clamps are closed by the straightened toggle 9, 10 the rocking member 84 occupies the position shown in Fig. 1, it being held in this position by a pulling spring 86 which is connected at one end to the bed and at the other end to the connection 82. Just after the pull-down fingers have been operated to pull down the thread, as shown by full lines Fig. 9, the member 84 is given a turning movement about its pivot 85 into the position shown in Fig. 6. This turning movement accomplishes two things. It releases the clamp 4 by breaking the toggle 9, 10, and it also swings the cutters into thread-cutting position thereby to cut the thread.

The member 84 is provided with a roll 87 which engages the toggle member 9 as the clamp-releasing member swings into the position shown in Fig. 6, such engagement operating to break the toggle 9, 10, which will, of course, release the clamps 4 in a well known way. This swinging movement of the member 84 also operates to draw the connection 82 to the left Fig. 1 into the position shown in Fig. 6 and since this connection is secured to the toggle member 75 such movement of the connection 82 will partially straighten the toggle 74, 75 as shown in Fig. 4 thus swinging the thread-cutting members 59, 60 toward each other. This swinging

movement is in a plane parallel to the work and since the pull down pulls the thread down so that the thread extends from the pull down upwardly to the work the cutters while swinging in this horizontal plane act on the thread between the pull-down and the work as indicated in Fig. 9 and thus cut the threads close to the work. The threads which are cut are all those which extend from the work to the throat plate and will include the two sides of the loop 33 of the needle thread and the under thread 35 and the cord 36, if such under thread and cord are used.

The cutting members 59, 60 may have any desired construction. As herein shown 60 represents a cutting block and 59 a cutter operating against said block, this construction being one which ensures positive cutting of the thread because of the toggle lever action by which the arms 61, 62 are actuated.

The member 84 is given its movement by means of the lever 22. For this purpose said lever has extending therefrom a pin or projection 88 adapted to engage a shoulder 89 formed on the member 84.

The main cam 8 is provided with a cam surface 90 which is situated so that it will engage the roll 24 on the lever 22 just after the pull-down fingers have operated to pull down the length of thread as shown in Fig. 9. As the cam surface 90 rides onto the roll 24 the lever 22 will be depressed, such depressing movement causing the projection 88 to act on the shoulder 89 and thereby swing the member 84 into the position shown in Fig. 6. The rise of the cam projection 90 is such as to give the lever 22 sufficient downward movement to cause it to wipe by the shoulder 89 and as a result the cutters will be given a quick cutting movement and then will be released and returned to their normal position.

For ensuring the return of the cutters to their normal position the toggle 74 has rigid therewith an arm or extension 79 having at its end a roll 80 and the turret is provided with a cam surface 104 situated to engage the roll 80 as the turret is turned after the frame 7 has completed its forward movement. The engagement of the cam surface 104 with the roll 80 will break the toggle 74, 75 and thus positively open the cutters away from each other.

105 indicates an adjustable stop screw which may be employed to limit the straightening movement of the toggles 74, 75 thereby to prevent undue pressure or strain from coming on the arms 61, 62.

The construction of the swinging member 84 and the toggle arm 9 is such that the first swinging movement of the member 84 will release the clamps and further swinging movement will actuate the cutter. The arm 9 is shown as having a curved surface 106 which is concentric with the pivot 85 when the

toggle 9, 10 is broken. Consequently when said toggle has been broken by the initial swinging movement of the clamp-releasing member 84 and the clamps have been released then during further swinging movement of the member 84 the roll 87 will move over the concentric surface 106 and thus such further swinging movement will not affect the toggle.

It will be further noted that the point of connection 83 of the link 82 with the swinging member 84 is such that when the cutters are brought into cutting position as shown in Fig. 4 the member 83 is nearly in line with the pivot 85 and thus a maximum cutting force will be applied to the cutters and positive cutting of the thread will be ensured.

The machine comes to rest finally with the roll 24 resting on the surface 91 of the cam 8 between the cam projections 90 and 25 and thus the lever 22 is in position to act on the arm 26 to close the clamps when the machine is again started in operation.

It will thus be seen that the clamps 4 are released before the threads are cut. The cam for operating the cutter block 28, however, is so timed that said cutter block is closed down onto the work just before the thread is cut so that at the time the threads are being cut the work is being gripped between the block 28 and the buttonhole cutter 27. As the cutter block has its complete downward movement it forces the work down over the cutter as shown by dotted lines 107, Fig. 9 and this has the advantage that it places the work in more advantageous position for the cutting of the threads. Hence although the work clamps 4 are raised from the work during the thread cutting operation yet the work is held between the buttonhole cutter 27 and the cutter block 28.

The under thread 35 extends up through the hollow tube 92 situated axially of the turret and from the latter passes over suitable guides to a tension device 93 comprising two spring-pressed tension disks between which the thread is led. From the tension disk the thread extends up through an eye 108 on the end of a spring tension finger 109 and thence passes to the under thread mechanism 99. During the sewing operation the yielding finger 109 will have a varying position but will be frequently in the position shown in dotted lines Fig. 5.

During the movement of the parts from stitching to buttonhole cutting position and while the thread is being pulled off the strain on the under thread will straighten the finger 109 so that the thread will be led from the tension to the under thread mechanism as shown by full lines Fig. 5. When the threads are cut the resiliency of the spring arm 109 will cause it to move into the dotted line position Fig. 5 and in so doing a length of the under thread will be pulled from some source. If

the tension 93 is still applied this movement of the spring arm 109 from the full to the dotted line position will draw the under thread back through the throat plate and will thus leave insufficient length of under thread to properly form the first stitch at the next stitching operation.

I have, therefore, provided means to prevent this from happening. One such means is shown in Fig. 5 wherein a device is illustrated for relieving the tension 93 on the thread just before the thread is cut and after a length of thread has been pulled through the throat plate so that before the thread is cut the resiliency of the arm 109 in swinging from the full to the dotted line position Fig. 5 will draw on the thread from the source of supply. This tension-releasing device is in the form of a tension-releasing lever 94 pivoted to the turret at 95 and having a wedge-shaped end 96 adapted to enter between the tension disks and separate them. This tension-releasing lever 94 is normally held in its inoperative position as shown in full lines Fig. 5 by the spring 97 and said lever is provided with an extension 98, the upper end of which is confined in a slot in the cam extension 65 and normally occupies a position within the cam groove 66. As the follower 68 traverses through the cam groove 66 it engages the upper end 98 of the lever 94 and swings the latter into the dotted line position thus causing the wedging portion 96 thereof to separate the tension disks and thus relieve the tension on the under thread 35. This occurs before the thread is cut and hence after the thread is cut there will be no unusual tension on the under thread tending to pull it back through the throat plate.

Another device for accomplishing this is shown in Figs. 10 and 11. In this embodiment of the invention the cam member 65 has pivotally mounted thereon at 110 an arm 111 which is provided with a cam portion 112 that overlies the cam groove 66 so that as the follower 68 passes through the cam groove 66 it engages the cam surface 112. The arm is provided with a curved end 113 situated adjacent the resilient finger 109. The arm 111 is acted on by a spring 114 which normally holds it in the full line position Fig. 11. As the follower 68 passes through the cam groove 66 and engages the cam surface 112 the arm 111 will be swung from the full to the dotted line position and in so doing will force the arm 109 positively backwardly to the dotted line position Figs. 5 and 11 which is its normal position when no strain is applied to the thread. This occurs while the thread is being pulled off and the arm 111, therefore, holds the thread take-up arm 109 in its backward position while the thread is being pulled off and thus compels the thread to be drawn through the tension at this time. Therefore, the arm 109 is in its backward position shown

in dotted lines Fig. 5 and there will be no tendency for it to draw the under thread back through the throat plate.

While I have illustrated herein a selected embodiment of my invention I do not wish to be limited to the constructional features shown.

I claim:

1. In a sewing machine adapted to perform a predetermined sewing operation and then come to rest, the combination with stitch-forming mechanism and work-holding means movable relative to each other during and subsequent to the stitching operation, of a throat plate through which thread is led to the work, the relative movement after the stitching operation drawing out a length of thread from the throat plate, means to separate said thread from the under side of the work, and other means operating independently from the last-named means to cut the thread close to the work.

2. In a sewing machine adapted to perform a predetermined sewing operation and then come to rest, the combination with stitch-forming mechanism and work-holding means movable relative to each other during and subsequent to the stitching operation, of a throat plate through which thread is led to the work, the relative movement after the stitching operation drawing out a length of thread from the throat plate, means to engage the thread between the throat plate and the work and carry it away from the work, and other means operating independently from the last-named means to cut the thread close to the work.

3. In a sewing machine adapted to perform a predetermined sewing operation and then come to rest, the combination with stitch-forming mechanism and work-holding means movable relative to each other during and subsequent to the stitching operation, of a throat plate through which thread is led to the work, the relative movement after the stitching operation drawing out a length of thread from the throat plate, a pull-down to engage said length of thread and separate it from the work, and other means to cut the thread close to the work.

4. In a sewing machine adapted to perform a predetermined sewing operation and then come to rest, the combination with stitch-forming mechanism and work-holding means movable relative to each other during and subsequent to the stitching operation, of a throat plate through which thread is led to the work, the relative movement after the stitching operation drawing out a length of thread from the throat plate, means to separate said thread from the under side of the work, and a cutter operating independently of said last-named means and in a plane parallel to the work to cut the thread close to the work.

5. In a sewing machine adapted to perform a predetermined sewing operation and then come to rest, the combination with stitch-forming mechanism and work-holding means movable relative to each other during and subsequent to the stitching operation, of a throat plate through which thread is led to the work, the relative movement after the stitching operation drawing out a length of thread from the throat plate, means to engage the thread between the throat plate and the work and carry it away from the work, and a cutter operating independently of said last-named means and in a plane parallel to the work to cut the thread close to the work.

6. In a sewing machine adapted to perform a predetermined sewing operation and then come to rest, the combination with stitch-forming mechanism and work-holding means movable relative to each other during and subsequent to the stitching operation, of a throat plate through which thread is led to the work, the relative movement after the stitching operation drawing out a length of thread from the throat plate, a pull-down to engage said length of thread and separate it from the work, and a cutter operating in a plane parallel to the work to cut the thread close to the work.

7. In a sewing machine adapted to perform a predetermined sewing operation and then come to rest, the combination with stitch-forming mechanism, of work clamps for clamping the work, said stitch-forming mechanism and work clamps having a relative movement at the completion of the sewing operation to draw off a length of thread, a pull-down acting on said length of thread to separate it from the work, clamp-releasing mechanism, and means actuated thereby to cut the thread between the pull-down and the work.

8. In a sewing machine adapted to perform a predetermined sewing operation and then come to rest, the combination with stitch-forming mechanism, of work clamps, said stitch-forming mechanism and work clamps having a relative movement at the completion of the sewing operation to draw off a length of thread, means to separate said length of thread from the work, other means to trim the thread at the end of the sewing operation, and means actuated thereby to release the clamps.

9. In a sewing machine, the combination with work-clamping means, of stitch-forming mechanism, said work-clamping means and stitch-forming mechanism having a relative movement at the completion of the sewing thereby to draw off a length of thread, a pull-down to engage said thread and separate it from the work, clamp-releasing means, and means to cut the thread between the pull-down and the work after the work is unclamped.

nism, said work-clamping means and stitch-forming mechanism having a relative movement at the completion of the sewing thereby to draw off a length of thread, a pull-down 5 to engage said thread and separate it from the work, a thread cutter to cut the thread between the pull-down and the work, thread-cutter operating means, and means actuated thereby to release the clamps prior to the cutting 10 of the thread.

20. In a sewing machine, the combination with work-holding means, stitch-forming mechanism including a needle operating above the work, an under-thread-manipulating 15 mechanism carrying an under thread, a turret on which the under-thread-manipulating mechanism is mounted, a throat plate carried by the turret and through which the under thread passes to the work, a resilient 20 take-up finger carried by the turret and through which the under thread passes, said stitch-forming mechanism and work-holding means having a relative movement after the completion of the sewing by which a length 25 of thread is drawn out through the throat plate, means to cut said thread between said throat plate and the work, and means operated by the movement of the turret to engage 30 said finger and hold it from flexing movement while the thread is being drawn out.

21. In a sewing machine, the combination with work-holding means, stitch-forming mechanism including a needle operating above the work, an under-thread-manipulating 35 mechanism carrying an under thread, a turret on which the under-thread-manipulating mechanism is mounted, a throat plate carried by the turret and through which the under thread passes to the work, a resilient take-up finger carried by the turret and through 40 which the under thread passes, said stitch-forming mechanism and work-holding means having a relative movement after the completion of the sewing by which a length of thread 45 is drawn out through the throat plate, a tension for the under thread carried by the turret, and means operated by the movement of the turret to relieve the tension on the under thread while said thread is being 50 drawn out through the throat plate.

22. In a sewing machine adapted to perform a predetermined sewing operation and then come to rest, the combination with 55 stitch-forming mechanism and work-holding means movable relative to each other subsequent to the stitching operation thereby to draw out a length of thread, of non-cutting means to separate said thread from the under side of the work, and a cutter operating in a plane parallel to the work to cut the thread close to the work.

23. In a sewing machine, the combination with work-holding means, of stitch-forming mechanism including a needle operating 60 from above the work, thread-manipulating

mechanism operating beneath the work, a turret on which said mechanism is mounted, said stitch-forming mechanism and work-holding means having a relative movement after the completion of the sewing by which a 70 length of thread is drawn out, non-cutting means operated by the movement of the turret to separate said length of thread from the work, and means to cut the thread.

24. In a sewing machine adapted to perform a predetermined sewing operation and then come to rest, the combination with stitch-forming mechanism including a needle operating above the work and under thread 75 mechanism beneath the work, of work-holding means, a turret on which the under thread mechanism is mounted, said stitch-forming mechanism and work-holding means having a relative movement after the completion of the sewing by which a length of thread is 80 drawn out, a main cam controlling the operation of the machine, means operated by the movement of the turret to separate said length of thread from the work, and means actuated by the cam to cut the thread. 85

25. In a sewing machine adapted to perform a predetermined sewing operation and then come to rest, the combination with stitch-forming mechanism including a needle operating above the work and under 90 thread mechanism beneath the work, of work-holding means, a turret on which the under thread mechanism is mounted, said stitch-forming mechanism and work-holding 95 means having a relative movement after the completion of the sewing by which a length of thread is drawn out, a main cam controlling the operation of the machine, non-cutting means operated by the movement of the turret to separate said length of thread from the work, and means actuated by the cam to 100 cut the thread. 105

26. In a sewing machine, the combination with work-clamping means, of stitch-forming means including a needle operating above 110 the work and under thread mechanism beneath the work, a turret on which the under thread mechanism is mounted, said work-clamping means and stitch-forming mechanism having a relative movement at the completion of the sewing operation by which a length of thread is drawn out, clamp-releasing means, means actuated by the turret to 115 separate said length of thread from the work before the clamps are released, and means to cut the thread after the clamps are released. 120

27. In a buttonhole sewing machine, the combination with work-clamping means, of stitch-forming mechanism, a buttonhole cutter, means to release the clamps at the end 125 of the stitching operation, means to trim the thread after the clamps are released, and means to actuate the buttonhole cutter to cause it to hold the work while the thread 130 is being trimmed.

28. In a buttonhole sewing machine, the combination with stitch-forming mechanism, of work-clamping means, and means operative at the end of the sewing operation first 5 to release the clamps, then to trim the thread and then to cut the buttonhole.

29. In a buttonhole sewing machine, the combination with stitch-forming mechanism, of work-clamping means, a thread trimmer, 10 a buttonhole cutter, means to release the clamps at the end of the sewing operation and subsequently to actuate the trimmer, and means to actuate the buttonhole cutter to cause it to grip the work while the thread is 15 being trimmed and thereafter to cut the buttonhole.

30. In a sewing machine adapted to perform a predetermined sewing operation and then come to rest, the combination with 20 stitch-forming mechanism and work-holding means movable relative to each other during and subsequent to the stitching operation, of a throat plate through which a thread is led to the work, the relative movement after the 25 stitching operation drawing out a length of thread from the throat plate, non-cutting means movable downwardly at substantially right angles to the work to separate said thread from the under side of the work, other 30 means movable in a different direction to cut the thread close to the work, and means to operate the non-cutting means and the cutting means successively.

31. In a sewing machine adapted to perform a predetermined sewing operation and then come to rest, the combination with 35 stitch-forming mechanism, of work-holding means, said stitch-forming mechanism and work-holding means having a movement relative to each other at the end of the sewing operation thereby to draw out a length of thread, non-cutting means movable downwardly in a direction substantially at right 40 angles to the work to separate the thread from the under side of the work, and thread-cutting means movable in a different direction 45 to cut the thread close to the work.

32. In a sewing machine adapted to perform a predetermined sewing operation and then come to rest, the combination with 50 stitch-forming mechanism, of work-holding means, said stitch-forming mechanism and work-holding means having a movement relative to each other at the end of the sewing 55 operation thereby to draw out a length of thread, non-cutting means movable downwardly in a direction substantially at right angles to the work to separate the thread from the under side of the work, thread-cutting means movable in a different direction 60 to cut the thread close to the work, and means for operating the non-cutting means and the cutting means successively.

33. In a sewing machine adapted to perform a predetermined sewing operation and

then come to rest, the combination with stitch-forming mechanism, of work clamps, said stitch-forming mechanism and work clamps being movable relative to each other during and subsequent to the stitching operation, a throat plate through which thread is led to the work, the relative movement after the stitching operation drawing out a length of thread from the throat plate, means to separate said thread from the under side of the work, means to release the work clamps, and means operating independently from the means which separates the thread from the under side of the work to cut the thread close to the work after the clamps are released. 70 75 80

In testimony whereof, I have signed my name to this specification.

AXEL F. CARLSON.
